COATING MACHINE FOR APPLYING DRY
PARTICULATE MATERIAL

Jens A. Paasche, Wilmette, Ill.

Application May 21, 1949, Serial No. 94,673

8 Claims. (Cl. 118—312)

1

The present invention relates generally to a machine for coating objects, and more particularly for coating a moving sheet with powder, bronze flock, or other comminuted dry coating material.

A common method of applying such coating material to an object is directing an air stream, carrying the coating material, against the surface of the object to be coated. Inherent in this method of coating are the problems of applying the coating uniformly and recovering the dry material which does not adhere to the sheet so that such material is neither wasted nor allowed to contaminate the surrounding atmosphere.

The main objects of this invention, therefore, are to provide an improved machine for applying a coating of powder, bronze flock, or other small particles of dry coating material to a traveling sheet of rubber, cloth, paper, or similar article, which material may or may not have an adhesive surface; to provide an improved form of housing adapted to direct a material-laden air stream under pressure against the surfaces of the moving sheet and to facilitate the recovery of the surplus material not adhering to the sheet; to provide an improved arrangement of two parallel, substantially closed circuits of material-laden air streams from one of which circuits the desired amount of material-laden air under pressure is diverted to the housing for application of the material onto the sheet traveling through said housing and to which circuit is returned the surplus material not adhering to the sheet, and the other of which circuits filters air from the material-laden air stream sufficient to compensate for the air drawn into the housing during the spraying operation; to provide an improved arrangement of said housing affording the admission of air into said air streams sufficient to prevent the escape of material into the atmosphere surrounding said housing; to provide improved means for adding a measured supply of fresh coating material to the air stream; and to provide a machine of this kind which is inexpensive to manufacture, easy to install, and effective in operation.

In the accompanying drawings:

Fig. 1 is a side elevation of an improved coating apparatus constructed in accordance with this invention;

Fig. 2 is an enlarged, fragmentary detail of the applicator, taken on the line 2—2 of Fig. 1;

Fig. 3 is a reduced plan view of the machine, as shown in Fig. 1;

Fig. 4 is an enlarged, transverse, vertical, sectional detail taken on the line 4—4 of Fig. 3;

2

Fig. 5 is a perspective view of the spreading nozzle which is used with the applicators;

Fig. 6 is an enlarged, longitudinal, sectional detail of the spreading nozzle shown in Fig. 5; and

Fig. 7 is a transverse sectional detail of the same.

The herein-shown preferred form of a coating machine, constructed in accordance with this invention, comprises a material-applying housing 10 and a material-circulating mechanism 11 co-acting to direct an air spray of dry coating material against a sheet 12 as it is caused to traverse a vertical path through the housing 10.

The housing 10 comprises a pair of outer walls 14 and two pairs of inner walls 15 and 16. These walls are arranged to form a pair of applicators or nozzles 17 and 18 and a pair of collecting chutes 19 and 20. The applicators and collectors 15 are located on opposite sides of the path of the moving sheet 12 and above and below an applicating chamber 21. Dispensing nozzles 22 are arranged at the upper ends of the applicators 17 and 18 and collector tubes 23 are located in the lower ends of the collecting chutes 19 and 20. The nozzles or spreaders 22 and collecting tubes 23 are connected to the coating-material-circulating-mechanism 11, as will be pointed out more fully hereinafter.

The outer walls 14 of the housing 10 are of identical form. Each comprises an upper section 24, an intermediate section 25, and a lower section 26, angularly disposed with respect to each other. The opposed sections 24 and 26, as will be most apparent from Fig. 1, are of truncated triangular form with the respective bases 27 and 28 opposed and spaced apart by the respective rectangular-shaped intermediate section 25. As will be most apparent from Fig. 4, the outside walls 14 are so arranged that the upper sections 24 converge inwardly toward their bases 27, whereas the lower sections 26 converge toward the apexes away from the bases 28. Thus, the applicating chamber 21, in transverse cross-section, is of truncated triangular form with the narrow part along the base lines 27 and the wider part along the base lines 28 of the respective upper and lower sections.

The pairs of inner walls 15 and 16 are substantially coextensive with the outer-wall sections 24 and 26. The inner walls 15 are closely arranged with the respective outer wall sections 24, with each inner wall converging at its base toward the corresponding base of the outer wall section 24. Along their base edges the inner walls 15 are doubled back upon themselves to

form reinforcing peripheral flanges 20. By means of rivets 30 and spacing rings 31 the lower edges of the inner walls 15 are anchored in spaced relationship to the respective outer-wall sections 24 (see Fig. 2). There is thus formed along the lower edges of the inner walls 15 a narrow slot 32 through which the coating material is discharged onto the sheet 12 moving through the chamber 21.

The lower inner walls 16 have their upper edges doubled back upon themselves to form reinforcing peripheral flanges 33 (see Fig. 4), which edges are closely spaced on opposite sides of the path of the moving sheet 12. These inner walls converge toward the lower ends of the opposed lower wall sections 26 wherewith they form the collecting chutes 19 and 20 for the surplus coating material.

Wires 34 are arranged at intervals connecting the upper flanged edges of the lower inner walls 16 with the intermediate wall sections 25. These wires serve not only to brace the inner walls 16, but also to properly guide the sheet 12 out of the chamber 21 into the path between the collecting chutes 19 and 20.

The form of the nozzles 22 is most clearly shown in Figs. 5, 6, and 7. Each comprises a tubular part 35, the outer ends of which are closed, with which is associated a flanged inlet 36 and a flat arcuate-shaped extension 37. The walls of the extension converge toward the median point of the arc and a slot 38 is formed in the periphery of the arcuate extension 37, through which the coating material is discharged into the applicators 17 and 18. As will be noted from Figs. 5 and 6, particularly, the slot 38 is larger at its inner ends than at its median point so as to insure a larger quantity of the material being dispersed toward the outwardly-flaring edges of the applicators 17 and 18. The inlet 36 is arranged at right angles to the plane of the slot 38 so that material is discharged against the opposite wall directly above the slot 38. This insures the best possible uniform dispersion of the material through the slot 38.

The nozzles 22 rest on and are suitably secured to flanges, with suitable intervening gaskets, formed at the truncated apexes of the respective inner walls 15 and the outer-wall sections 24 of the applicators 17 and 18.

The collector tubes 23 are likewise secured to arcuate-shaped flanges formed at the truncated apexes of the inner walls 16 and the outer-wall sections 26.

The material-circulating mechanism 11 comprises a blower 39, the tandem material-circulating conduits 40 and 41, a material-delivering conduit 42, a separator 43, and a material-supply magazine or hopper 44. These combine to provide two closed parallel channels through which is simultaneously circulated material-laden air streams, from one of which circuits is diverted the required material-laden air to coat the sheet 12, and the other of which circuits provides an escape of filtered air sufficient to compensate for the air drawn in through the housing 10 during the coating operation.

The blower 39 is of the centrifugal type, set on a standard 45 above the top of the housing 10 and is driven by a motor 46. The inlet and discharge of the blower are connected to the conduits 40 and 41 by trunk connections 47 and 48.

The conduit 40 leads from the trunk connection 48 with the blower discharge to the two collector tubes 23 for the housing 10, which collector tubes,

at their other ends, are joined with the trunk connection 47 connecting with the blower inlet, thus completing one of the circuits. In this circuit, the surplus material not adhering to the sheet 12, as it passes through the housing 10, is drawn into the collector chutes 19 and 20 and picked up by the air stream passing through the tubes 23.

The conduit 41 leads from the trunk connection 48 with the blower discharge to the separator 43 which, in turn, is connected with the trunk connection 47 which leads to the blower inlet. In this circuit, the powder, bronze flock, or other comminuted material is filtered from the air stream, the air escaping through the separator outlet 56 to compensate for the air drawn into the chamber 21 in the housing 10 between the inner ends of the inner walls 15 and 16.

The separator 43 comprises a casing 49 within which is suspended a fabric screen 50. At its lower end the casing outlet is funneled and connected to the trunk connection 47 leading to the inlet of the blower 39.

The fabric screen 50 is attached at its lower end at the base of the casing 49 around the outlet and at its upper end is secured to a plate 51 embracing the conduit 41 and suspended from a motor-driven agitator 52.

The agitator 52 serves to keep the powder, bronze flock, or other comminuted material from accumulating on the fabric screen 50 and so clogging the pores or meshes as to prevent the escape of the air through the separator exhaust 56.

Butterfly damper valves 53, 54, and 55 are arranged in the conduits 40 and 41, and in the collector exhaust 56. The adjustment of these dampers permits control of the flow of the material-laden air streams through the conduits 41 and 42 and their connections, and, consequently, determine the character of the material-laden air stream which is directed through the conduit 42 for the application of the material to the sheet 12 as it moves through the housing 10.

The material supply magazine or hopper 44 is a vertically-disposed cylinder with a funnel-shaped bottom 55 connected by a short nipple 56 to feed fresh material into the conduit 40, intermediate the collector tubes 23 and the trunk connection 47 with the inlet of the blower 39. A feed auger 57 in the nipple 56 and a wire agitator 58 in the magazine are operated by a motor 59 to deliver measured amounts of the powder, bronze flock, or other comminuted material to the air stream circulating through the conduit 40 on its way to the blower 39.

The herein-shown motor 59 is air-driven and its connection to a suitable source of compressed air is through an air conditioner 60 designed to remove moisture, oil, or other impurities in the air and thereby insure the effective operation of the motor 59.

A door 61 in the magazine 43 permits fresh supplies of dry coating material to be added to the magazine or hopper as needed.

In operation the sheet 12 which is to be coated is moved downwardly between the walls 15 and 16 of the housing 10, traveling over suitable rollers such as shown at 62 and 63 of Fig. 4. An air stream laden with powder, bronze flock, or other comminuted material is discharged through the slots 32 of the applicators 17 and 18 on that portion of the sheet 12 which is within the spraying chamber 21. By reason of the form of the nozzles 37 and their position within the applicators

17 and 18 the coating material is uniformly spread across the full width of the sheet 12.

The air stream of material circulating through the conduit 40 sets up a suction in the collector chutes 19 and 20. Obviously, this causes air to be drawn in through any open spaces around the spray chamber 21 such as, for example, between the walls 15 and walls 16, as indicated by the arrows in Fig. 4. Accordingly, a slight amount of air will be drawn in between the sheet 12 and the lower ends of the inner walls 15 of the applicators 17 and 18. As a consequence of this suction and the inflowing air, any surplus material not adhering to the sheet 12 is drawn down through the collector chutes 19 and 20 into the tubes 23, thereby being returned to and becoming a part of the air stream circulating through the conduit 40 with its trunk connections 47 and 48 and the blower 39.

The material in the air stream produced by the blower 39 discharged through the trunk connection 48 divides, and part of it flows through the conduit 41 and hence through the separator 43. In the separator, sufficient air to compensate for that drawn into the spraying chamber 21, as hereinbefore explained, is filtered out through the screen 50 and escapes through the separator exhaust 56.

The setting of the valves 53, 54, and 55 determines the portions of the material-laden air stream, emerging from the blower 39 through the trunk connection 48, which will pass through the respective conduits 40 and 41 and the portion thereof which will be diverted from the blower 39 into the conduit 42 to be delivered to the applicators 17 and 18.

Although but one specific embodiment of this invention has been herein shown and described, it will be understood that details of the construction shown may be altered without departing from the spirit of the invention as defined by the following claims.

I claim:

1. In a machine for applying small particles of dry coating material simultaneously to the opposite faces of a traveling sheet, the combination of a housing comprising a pair of oppositely disposed, vertically extending outer walls and pairs of upper and lower inner walls arranged on opposite sides of the path of travel of the sheet, each of said outer walls being formed of three angularly-disposed sections including upper and lower sections of truncated triangular form and an intermediate section of generally rectangular form, said upper and lower sections being inclined inwardly relative to the respective intermediate sections and with their bases opposed and vertically spaced apart by said rectangular intermediate sections, said pairs of upper and lower inner walls being substantially coextensive with the respective upper and lower outer-wall sections, said upper inner walls being arranged with their bases slightly converging toward the adjacent outer-wall sections so as to provide applicators having narrow openings along the adjacent lateral edges of the respective intermediate wall sections through which material is directed onto the sheet, said lower inner-wall sections having their base edges closely spaced on opposite sides of said path with their truncated apexes converging toward the apex ends of said outer-wall sections, a material-spreading nozzle located between the truncated apexes of each of the upper outer-wall sections and their corresponding inner walls, a collector tube lo-

cated at the truncated apexes of each of said lower outer-wall sections and their corresponding inner walls, and a blower having its inlet connected to said collector tubes and an outlet connected to said nozzles so as to cause a continuous circulation of material through said housing.

2. In a machine for applying small particles of dry coating material simultaneously to the opposite faces of a traveling sheet, the combination of a housing comprising a pair of oppositely disposed, vertically extending outer walls and pairs of upper and lower inner walls arranged on opposite sides of the path of travel of the sheet, each of said outer walls including an upper section, an intermediate section, and a lower section, said pairs of upper and lower inner walls being substantially coextensive with the respective upper and lower outer-wall sections, said upper inner walls being arranged with their bases slightly converging toward the adjacent outer-wall sections so as to provide applicators having narrow openings along the adjacent lateral edges of the respective intermediate wall sections through which material is directed onto the sheet along the direction of travel of the sheet, said lower inner-wall sections having their base edges connected to the base edges of said lower sections of said outer walls and having their top edges located closely adjacent the sheet providing an opening for the sheet to leave the machine; a material spreading nozzle located between each of the upper outer-wall sections and their corresponding inner walls, a collector tube located at the bottom of each of said lower outer-wall sections and their corresponding inner walls; a blower having its inlet connected to said collector tubes and an outlet connected to said nozzles so as to cause a continuous circulation of material through said housing; and means connected to a blower outlet and adapted to separate the material not delivered to said nozzles and return such separated material to said blower inlet.

3. A coating machine for applying small particles of dry coating material to a vertically-traveling sheet comprising a pair of spaced, coextensive vertically-disposed walls of substantially triangular form, said walls being spaced apart at their apexes and converging therefrom toward each other to form a narrow opening along the bases of said walls adjacent said path and through which material is discharged against said sheet, and an arcuate-shaped nozzle located intermediate said walls in the region of their apexes, said nozzle having a pair of arcuate shaped side walls which define an opening having a gradually increasing width from its center towards the opposite ends of the opening.

4. A coating machine for applying small particles of dry coating material to a vertically-traveling sheet comprising a pair of spaced, coextensive vertically-disposed walls of substantially triangular form, said walls being spaced apart at their apexes and converging therefrom toward each other to form a narrow opening along the bases of said walls adjacent said path and through which material is discharged against said sheet, an arcuate-shaped nozzle located intermediate said walls in the region of their apexes, said nozzles having a pair of arcuate shaped side walls which define an opening having a gradually increasing width from its center towards the opposite ends of the opening, and a material-supply conduit connected to said nozzle to de-

liver material to said nozzle in a direction substantially perpendicular to the general plane of said nozzle.

5. A machine for applying particles of dry coating material to an object comprising, a housing defining a chamber for the reception of said object during the application of the material thereto, a blower, a conduit connecting said blower with said housing to deliver a material-laden air stream to impinge upon said object, other conduit means connecting the discharge of said blower by two separately-branching channels to the inlet of said blower for the continuous flow of two material-laden air streams, said housing having its outlet connected to one of said branch conduits for the redelivery of the surplus material in said housing to said blower inlet, and a separator interposed in the other said branch conduit and adapted to screen the material from the air stream for redelivery to said blower inlet.

6. In a system for applying small particles of dry coating material to an object, the combination of means defining a chamber for receiving the object to be coated and into which chamber said coating material is delivered in an air stream to be impinged upon the surface of said object, conduit means defining a pair of parallel closed air circuits, a blower having its inlet and discharge connected to both of said circuits to effect a simultaneous and continuous flow of air through said circuits, means for introducing a measured amount of dry coating material into one of said circuits, means for diverting from one of said circuits a material-laden air stream for delivery to said housing chamber, one of said circuits being connected to said chamber to withdraw the surplus of material not adhering to said object and returning said material to said one circuit, and a separator interposed in the other said circuit and adapted to permit an escape of filtered air commensurate with the air that is drawn into said housing chamber.

7. A coating machine for applying small particles of dry coating material simultaneously to

the opposite faces of a travelling sheet, comprising a pair of vertically disposed applicators and opposed collectors defining a vertical path for the sheet, an applicating chamber located intermediate said applicators and said collectors, said chamber having an inlet opening therein for receiving the sheet, said applicators being located at and directed away from said opening along the line of travel of the sheet, a material magazine, means for delivering material from said magazine to said applicators, said collectors being disposed below said chamber and being adapted to collect the surplus coating material that does not adhere to the sheet, and means for delivering to said applicators the surplus material drawn from said collectors.

8. A coating machine for applying small particles of dry coating material to a vertically-disposed traveling sheet comprising a pair of spaced, vertically-extending walls, said walls being spaced apart at their upper ends and converging therefrom toward each other to form a narrow opening at their lower ends, said opening being adjacent the path of travel of the sheet, and an arcuate shaped nozzle located intermediate said walls in the region of their upper ends, said nozzle having a pair of arcuate shaped side walls which define an opening having a gradually increasing width from its center towards the opposite ends of the opening.
